US00D813541S

(12) **United States Design Patent** (10) **Patent No.:** **US D813,541 S**
(45) **Date of Patent:** **** Mar. 27, 2018**

(54) **BASKET**

- (71) Applicant: **Discovery Inc.**, Ross, CA (US)
(72) Inventor: **Mark Levie**, Corte Madera, CA (US)
(73) Assignee: **DISCOVERY INC.**, Ross, CA (US)
(**) Term: **15 Years**
(21) Appl. No.: **29/560,243**
(22) Filed: **Apr. 4, 2016**

FIG. 1 is a perspective view of an example basket;
FIG. 2 is a front plan view thereof;
FIG. 3 is a rear plan view thereof;
FIG. 4 is a right side plan view thereof, with the left side plan view being a mirror image thereof;
FIG. 5 is a top plan view thereof; and,
FIG. 6 is a bottom plan view thereof.
The broken line showings of FIGS. 1-6 are for illustrative purposes only and form no part of the claimed design.
The dash-dot-dash broken lines indicate the boundaries of what is considered to be the claimed design and the dash-dot broken lines show portions of the design that form no part of the claimed design.

1 Claim, 4 Drawing Sheets
